TROUSERS CUFFS OR THE LIKE

William Fierman, St. Louis, Mo.

Application May 24, 1935, Serial No. 23,151

1 Claim. (Cl. 2-232)

This invention relates to certain new and useful improvements in trousers cuffs or the like, the peculiarities of which will be hereinafter fully described and claimed.

This invention belongs to that class of cuffs of trousers and the like, in which means are provided for a multiple cuff which can be successively renewed when the edge is worn off or soiled. The main objects of my invention therefore are to provide means first, for renewing successively the worn edge of a cuff on trousers or the like; second, for readily increasing the length of a trousers leg which has shrunk, at the same time that the cuff is renewed; and third, for providing such multiple cuff as above described which will be hidden from observation when first manufactured in the renewable portions that provide for the successive cuffs; and other points of construction hereinafter described and claimed.

In the accompanying drawing in which like reference numerals indicate corresponding parts, Fig. 1 represents a portion of a trousers leg provided with a cuff of my construction; Fig. 2, a similar view showing one renewal of the cuff forming its second bottom edge; Fig. 3, a similar view showing a third renewal; Fig. 4, a diagrammatic representation of the method of laying out a multiple cuff of my construction; Fig. 5, a detail diagram of the preliminary form of the loop forming the main portion of the cuff; Fig. 6, a view similar to Fig. 5 showing the loop being opened and the position of the folds formed in the loop in opening the loop; Fig. 7, a view similar to Fig. 6 showing the loop pressed nearly flat forming a box pleat; and Fig. 8, a view similar to Fig. 7 showing the next step in forming my cuff by turning up the bottom fold to hide the portions of the loop which are lesser in width, to form the first bottom edge of the cuff as set out by the tailor.

Referring to the drawing, the numeral 1 designates a trousers leg on the bottom of which a cuff of my construction is to be formed. In laying off the measurements for a cuff on a leg of a certain length, the required length is first laid out vertically to the mark designated by L in Fig. 4. This is to form the first bottom of the cuff, and a sufficient amount of material to form a cuff of my construction is measured to the point 2. From the point 2 a free end band S of sufficient width is measured upward to the point L1. This L1 will be so disposed after turning up the free end band as indicated by dotted lines, that L1 will form the first bottom and coincides with the point L before mentioned. From L1 I measure upward

to point 3 a distance substantially equal to the free end band before mentioned. From point 3 I measure upward twice the width of the proposed cuff to point 4 the middle of which is the point 5 on which the two widths of the cuff are folded so as to bring the points 3 and 4 together and a cuff in double width and parallel arrangement of layers as shown in Fig. 5. These folds at the points 3 and 4 are preferably basted together to maintain temporarily the arrangement of the double thickness of the loop.

Next I open this loop as indicated in Fig. 6 by forming intermediate folds 6 and 7 at points that will allow the fold 7 to project a suitable distance ($\frac{1}{4}$ inch) below the fold L1. When this opened loop is pressed flat as above stated, it is disposed as in Fig. 7 and forms what is known as a box pleat. The desired width (2 inches) of the first cuff is presented by distance between the lower fold 7 and the upper fold 6 in Fig. 7. The fold 7 however does not form the first bottom, but is turned upward as indicated in Fig. 7, so that the fold 7 projects above the fold 6 as shown in Fig. 8. The intermediate folds before mentioned define lesser portions of the loop which are hidden as in Fig. 8, when the loop is disposed in folds as in Fig. 8.

Referring again to Fig. 6, it is seen that the fold 6 divides one side of the loop into the portions A and B respectively, designating a smaller and greater width of that side of the loop. The intermediate fold 7 likewise divides the lower width of the double loop into the portions C and D, of which C is the greater width as it is determined by the amount of projection of the fold 7 below the fold L1 from which the free end band portion extends upward so that its top is adjacent to said folds 3 and 4 which have been basted together as before stated. Thus these folds 3 and 4 define a band E extending downward to point L1, and this band is substantially the same width as the free end band. When the loop has been opened from the position of Fig. 7 to form the box pleat as in Fig. 8, this band portion designated E combines with the loop portion C to form the width of the cuff from L1 up to 7, Fig. 8.

The fold 7 is then tacked at two or three points to the leg material and the folded top of the selvage is stitched to the fold 4, and the cuff is pressed flat by the tailor's goose.

The diagrammatic Fig. 8 corresponds to the similar section in Fig. 1 and the fold L1 constitutes the first bottom edge of my cuff.

As shown in Fig. 8, the hidden layer portions

behind the first outer cuff portion are disposed wholly above the near midway double folds at 4, and the free end band S and the lower portion E below these portions A B and D, form only two layers of material which can be exposed to wear when the first bottom fold L1, Figs. 1 and 8, is worn ragged. The midway folds at 4 and this free end band S, remain in their located position undisturbed while the upper fold 7, Fig. 8, has its tacked stitches cut loose from the leg material and turned down again as in Fig. 7 so that its folded edge projects below the worn folded edge L1 and thus forms a new single folded edge L2, Fig. 2. L1 in its worn condition is thus overlapped by two layers C and D, Fig. 7, since the fold 7 in Fig. 8 has been turned down again as in Fig. 7, and forms the new bottom edge L2 of the second cuff; and both these layers C and D, Fig. 7 are disposed outward from the two layers S and E of the first bottom edge L1 (now worn) which latter now tends to guard the new edge L2 from contact with the shoe of the wearer.

When this first bottom edge is frayed and it is desired to renew the cuff, the leg has generally shrunk in length under usage and cleaning operation, so that it is preferred that the second bottom L2, Fig. 2 shall be located a little below (about $\frac{1}{4}$ inch or so) the former edge L1. When the cuff has been formed as described in Figs. 7 and 8, this renewal is readily effected by cutting the points tacked in the fold 7 where it has been tacked to the leg; then turning downward the fold 7 to the same lower position of Fig. 7 which will bring the fold 7 below the former bottom L1 now frayed and presenting a new bottom edge L2 for the cuff. In this turning down motion, the face of the new cuff is formed by the portions B and D which were hidden as shown in Fig. 8, but are now available for presenting a new outer surface to the cuff as shown in Fig. 2.

Thus a new cuff is quickly provided and when pressed presents a fresh appearance and its bottom edge projects enough to make up, if desired, for the shrinkage of the trouser leg.

The third cuff may be formed when the bottom edge L2 has become worn, and this is indicated in Fig. 3. To make this third bottom edge in renewal, the stitching of the free end band to the main leg portion, as in Fig. 2, is cut and the cuff extended downward as indicated by dotted lines in Fig. 3. This provides sufficient material to form a new cuff by making a wider free end band portion 11 from the new edge L3 upward to a fold 9 in the leg portion which is one-half, or less, of the width previously indicated at A. This new fold 9 is nearer the new top 10 of the new cuff than the folds 3 and 4 were disposed in the previous arrangement. The extra length of the unfolded cuff, as indicated in Fig. 3, provides for the wider free end band 11, and the upper edge 10 of said cuff is tacked to the leg material and the cuff pressed as usual. This latter form of cuff is known as the "French" cuff and I show it as a third renewal of the bottom edge of my cuff after forming the first bottom L1 and the second bottom edge L2 as shown in Figs. 1 and 2 and described above. I lay no claim to this last form of "French" cuff by itself.

For example: in forming a cuff of two inch width by my construction, the length of the leg to the point L Fig. 4, is increased by five inches to include the free end band at point 2 Fig. 4. Then in the same figure I turn up the free end band which is one inch wide and locates the point

L1. The free end band in its turned up position is indicated by the dotted lines in this figure. Then measuring upward from L1 $\frac{7}{8}$ " to point 3 and then two inches and another two inches representing the double thickness of a two inch cuff, I reach the point 4 before mentioned. Then the material is folded at 3 and 4 and the folds brought adjacent to form the two inch double loop shown in Fig. 5. As previously mentioned the loop is so opened that a fold at point 7 divides the lower layer of the loop into the greater and lesser portions C and D by disposing the fold 7 a quarter inch for example below L1 in Fig. 6. The portions D and B Fig. 6, form the face of the box pleat shown in Fig. 7 of the desired two inch width, as the portion D is $\frac{7}{8}$ " and the portion B is $1\frac{1}{8}$ ", in the numerical example being given.

It will be observed that in Fig. 6, the upper loop portion AB is folded at 6, and then BD is folded at 5 by turning up fold 7 (Fig. 7), so as to make the first outer cuff portion CE (Figs. 8 and 1). This first outer cuff portion hides the layers ABD of said double fold in forming the first cuff (Figs. 8 and 1), and their bottom folded edges opposite 4, Fig. 8, are stitched to the adjacent free end band S. The band E and free end band S are formed by the inward single fold L1 and constitute a lower section of the first cuff. These connected layers ABD joining the leg to the upper fold 7, Fig. 8, are thus above said single fold (Fig. 8) and constitute an upper section of the first cuff. Being hidden behind the outer portion CE of the first cuff (Figs. 8 and 1) and above the two single layers SE, these double folds at 4 and hidden layers ABD, are not subject to destructive wear on the first bottom edge L1, Fig. 1, but are held in reserve and are available to form the second bottom edge L2 (Fig. 2) by turning down again the upper folded edge 7 (Fig. 8) so that it projects below L1 again as in Fig. 7, and presents BD as a second outer cuff portion as indicated in Fig. 2 and Fig. 7.

The bottom edges of said double folds forming the three hidden layers ABD, Fig. 8, behind the first outer cuff portion CE, are disposed approximately midway of the width of said cuff portion and are available to form the second outer cuff portion BD Fig. 7, by turning down again the top fold 7 so that it projects below the worn edge L1 of the first bottom edge.

The pleats or layers and their connecting folds form part of the trousers leg and extend circumferentially around the trouser leg, and form five layers in the upper section of the first cuff, Fig. 8, and two layers in the lower section. When the outer top fold 7 is turned down to form the second cuff, three layers are left above the middle of the cuff and four layers are then disposed in the lower portion of the second cuff—as shown in Fig. 7.

Therefore it is evident that a saving of cost to the owner of the trousers is effected in renewing a cuff of my construction after the bottom edge L1 has become frayed and the new edge L2 is desired, since it is only necessary to cut the tacking at the upper edge 7, Fig. 8, turn it down as in Fig. 7, and press the cuff in this adjusted position. This work can be done by the owner without the aid and cost of a tailor. In making the new edge L3, a tailor or seamstress may be required. Even a fourth renewal in the style of a "French" cuff may be obtained, if the balance of the trousers are in such a state as to warrant such fourth renewal.

While I have shown and described my multiple

cuff as applied to a trousers leg, it may be applied to other wearing apparel to which such a renewal of a frayed edge is desired.

I claim:

5 A trousers cuff or the like characterized by folding the bottom of a trousers leg into upper and lower sections of circumferential pleats, the upper section forming, with the adjacent leg portion, five layers having two connecting folds at
10 the top, and two at the bottom of the upper section and disposed approximately midway of, and

hidden behind, the outer layer that forms the upper half of the first outer cuff portion, and the lower section having two layers consisting of the lower half of the said cuff portion connected to an inner free end band by a bottom fold which forms the bottom edge of the first cuff; the bottom edge of the second cuff being formed by turning down the outer top fold and disposing said hidden layers and folds to form the second outer cuff portion, substantially as described. 5 10

WILLIAM FIERMAN.
